William Michael

UNITED STATES PATENT OFFICE.

EDWIN C. WASHBURN, OF ENGLEWOOD, NEW JERSEY.

TRUCK-BOLSTER.

1,367,645.

Specification of Letters Patent.

Patented Feb. 8, 1921.

Application filed June 18, 1920. Serial No. 389,995.

To all whom it may concern:

Be it known that I, EDWIN C. WASHBURN, a citizen of the United States, residing at Englewood, in the county of Bergen and 5 State of New Jersey, have invented certain new and useful Improvements in Truck-Bolsters; and I do hereby declare the following to be a full, clear, and exact description of the invention, such as will enable others 10 skilled in the art to which it appertains to make and use the same.

My present invention provides an improved truck bolster and includes also an improved process of making the same. A 15 novel feature of the present invention consists in first independently forming the compression and tension members of the bolster and in thereafter rigidly and permanently uniting the said members by casting the elements directly against the same.

The invention is illustrated in the accompanying drawings, wherein like characters indicate like parts throughout the several views.

25 Referring to the drawings, wherein like characters indicate like parts throughout the several views,

Figure 1 shows the improved bolster and certain parts of a truck frame partly in 30 elevation and partly in vertical section;

Fig. 2 is a plan view of the bolster and part of the truck frame;

Fig. 3 shows a part of a truck frame in side elevation and the bolster in end elevation;

Fig. 4 is a section on the line 4—4 of Figs. 1 and 2;

Fig. 5 is a perspective view showing the center casting or strut of the bolster;

40 Fig. 6 is a perspective view showing the cast so-called tie-plate;

Fig. 7 is a fragmentary perspective showing a portion of the compression member of the bolster and the center plate cast thereon; 45 and

Fig. 8 is a perspective view of one of the cast end caps of the bolster.

The numerals 9 and 10, indicate, respectively, the compression and tension members 50 of the bolster. The compression or top member 9 is a rolled steel channel, while the lower or tension member 10 is preferably a flat rolled steel bar. At their central or intermediate portions, the compression and 55 tension members 9 and 10 are spaced by a cast independently formed strut 11 that is formed with a central sleeve 12 and, at its

lower portion, is made to fit and rest upon the grooved central portion of the tension bar or member 10.

The center bearing plate 13 is cast directly onto and completely around the central portion of the compression member or bar 9 (see Fig. 7), but this plate is thus cast while the members 9 and 10 and strut 11 are in 60 relative positions shown in Fig. 1, at which time it will be noted the top of said strut is spaced from the web of the compression member 9. Also, this center bearing plate is formed with a sleeve portion 14, that 65 alines with the sleeve 12 of the strut and coöperates therewith to form a pintle pin seat. This sleeve 14 is cast through a perforation in the central portion of the web of the member 9. The strut and the compression member are thus united by the casting 70 of the center bearing plate, as stated.

By reference particularly to Figs. 4 and 5, it will be noted that the lower portion of the center plate 13 is cast into grooves and 80 around flanges of the strut 11, so that it becomes positively interlocked thereto.

To rigidly unite the lower portion of the strut 11 to the central portion of the tension member or bar 10, a flanged tie-plate 15 85 (see particularly Figs. 4 and 6) is cast against the said member 10 and over the bottom flange of said strut, while the said parts are in their proper relative positions. Preferably, this tie-plate 15 and the tension 90 bar or member 10 are perforated to extend the pintle seat.

By reference particularly to Figs. 1 and 8, it will be noted that the so-called bolster and caps 16 are hollow rectangular structures formed or cast independently of the other members of the bolster and provided with large rectangular cavities 17, in which the ends of the compression and tension members 9 and 10 are adapted to be inserted 100 with a large amount of clearance. In the process of making the bolster, the ends of said members 9 and 10 are inserted and properly positioned within the cavities 17 and then the said parts are rigidly and permanently united by casting metal 18 into the said seats so as to fill the same and form welded or semi-welded joints with the ends of said members 9 and 10. Thus, the ends of the compression and tension members of 110 the bolster are very rigidly united. In their sides, the bolster end caps 16 are formed with guide ribs 19 for coöperation with the truck bolsters. Attention may be here called

to the fact that in Fig. 7, the center bearing plate 13 is, for clearness, shown as disassociated from the strut 11, whereas, as a matter of fact, after it has been cast, it will 5 always be fast to the previously formed strut 11.

By reference to the sectional portion at the left in Fig. 1, it will be noted that the 10 ends of the compression and tension members 9 and 10 are perforated so as to permit the metal 18 to run therethrough and thus increase the strength of the bond.

So far as the present invention is concerned, the truck frame which carries the 15 novel bolster described may be of any approved construction, but as illustrated, is of the form disclosed and claimed in my companion application filed of even date herewith and entitled "Truck side frame 20 and process of producing the same." Referring briefly to the parts thereof, the numeral 20 indicates the bolster columns, the numerals 21, 22 and 23, respectively, the tension and compression members and bottom tie-bars, the numeral 24 indicates a cross transom, and the numeral 25 the bolster-supporting springs.

The invention above described eliminates use of bolts and rivets in the bolster and 30 thereby obtains a maximum of strength with a minimum of weight and a result of economy in the use of metal. It also reduces, to a minimum, the amount of casting required, on the bolsters, and permits 35 the use, in the compression and tension members, of commercial rolled steel, which is not only cheaper, but better for use in a truck bolster than cast metal.

What I claim is:

40 1. A truck bolster having in combination a compression member, a tension member, a case inclosing the ends of said members and a cast metal filling in said casing which forms a rigid structure with the said ends 45 and casing.

2. A truck bolster having in combination a compression member, a tension member, a casing inclosing the ends of said members having openings therein, and a cast metal 50 filling in said casing which fills said openings and forms a rigid structure with said ends and casing.

3. A truck bolster comprising independently formed compression and tension members and a strut formed independently thereof, said compression and tension members and strut being rigidly and permanently united by metal cast fast thereto.

4. A truck bolster comprising independently formed compression and tension members and a strut formed independently thereof, and an independently formed center bearing plate cast fast to said compression member and strut.

5. A truck bolster comprising independently formed compression and tension members and a strut formed independently thereof, an independently formed center bearing plate cast fast to said compression member and strut, and a tie-plate cast fast 70 to said tension member and to said strut.

6. A truck bolster comprising independently formed compression and tension members, a strut and bolster end caps, all independently formed but rigidly and permanently united by metal subsequently cast 75 fast thereto.

7. A truck bolster comprising independently formed compression and tension members, a strut and bolster end caps, all independently formed but rigidly and permanently united by metal subsequently cast 80 fast thereto, and including a center bearing plate cast to form against and rigidly unite said strut and compression member. 85

8. The process of making truck bolsters, which consists in first independently forming the compression and tension members thereof and a strut, and thereafter rigidly and permanently uniting said elements by 90 casting metal fast thereto.

9. The process of making truck bolsters, which consists first in independently forming compression and tension members, a strut and bolster end caps, and thereafter 95 properly assembling said elements and rigidly and permanently uniting the same by casting metal fast thereto.

10. The process of making truck bolsters, in independently forming compression and tension members and a strut, in assembling said elements, and in rigidly uniting said strut to said compression member by casting 100 a center bearing plate fast thereto in the forming of said plate. 105

11. A bolster comprising tension and compression members having a strut cast through its compression member.

12. A bolster having a center plate cast around its compression member. 110

13. A bolster having a center plate cast through and around its compression member.

14. A bolster having upper and lower longitudinal members having a strut cast 115 into interlocking engagement therewith.

15. A bolster having a separately formed strut and co-operating tension and compression elements cast into interlocking engagement with the strut and uniting the same 120 thereto.

16. A bolster having an end casting chambered to receive the bolster member and secured thereto by a filler cast therein.

In testimony whereof I affix my signature. 125

EDWIN C. WASHBURN.
